US0D1060275S

(12) **United States Design Patent** (10) **Patent No.:** **US D1,060,275 S**
(45) **Date of Patent:** ** *Feb. 4, 2025

(54) **CONTROL DEVICE**

(71) Applicant: **Lutron Technology Company LLC**,
Coopersburg, PA (US)

(72) Inventors: **Gregory Altonen**, Easton, PA (US);
Susan Hakkarainen, Doylestown, PA (US); **Jason C. Killo**, Emmaus, PA (US); **Brad Michael Kreschollek**, Bethlehem, PA (US); **Noel Mayo**, Philadelphia, PA (US); **Matthew Philip McDonald**, Phoenixville, PA (US)

(73) Assignee: **Lutron Technology Company LLC**,
Coopersburg, PA (US)

(*) Notice: This patent is subject to a terminal disclaimer.

(**) Term: **15 Years**

(21) Appl. No.: **29/911,685**

(22) Filed: **Sep. 7, 2023**

Related U.S. Application Data

(63) Continuation of application No. 29/858,760, filed on Nov. 3, 2022, now Pat. No. Des. 1,001,752, which is a continuation of application No. 29/787,466, filed on Jun. 7, 2021, now Pat. No. Des. 969,757, which is a continuation of application No. 29/724,070, filed on Feb. 12, 2020, now Pat. No. Des. 924,184, which is a continuation of application No. 29/655,322, filed on Jul. 2, 2018, now Pat. No. Des. 879,055, which is a continuation of application No. 29/594,200, filed on Feb. 16, 2017, now Pat. No. Des. 837,168.

(57) **CLAIM**

The ornamental design for a control device as shown and described.

DESCRIPTION

FIG. 1 is a front perspective view of a control device showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The dashed broken lines illustrate structure or features which form no part of the claimed design.

1 Claim, 3 Drawing Sheets
